UNITED STATES PATENT OFFICE.

BENJAMIN W. TUCKER, OF NEWARK, NEW JERSEY.

ELECTRIC-RAILWAY SYSTEM.

SPECIFICATION forming part of Letters Patent No. 674,108, dated May 14, 1901.

Application filed January 30, 1901. Serial No. 45,304. (No model.)

To all whom it may concern:

Be it known that I, BENJAMIN W. TUCKER, a citizen of the United States, and a resident of Newark, in the county of Essex and State 5 of New Jersey, have invented certain new and useful Improvements in Electric-Railway Systems, of which the following is a specification.

This invention relates to certain improvements in safety electric-railway systems; and 10 the objects and nature of the invention will be apparent to those skilled in the art when considered in the light of the following description of the accompanying drawings, which illustrate an example among many constructions within the spirit and scope of my 15 invention.

The invention consists in certain novel features in construction and in combinations and arrangements of parts, as more fully and particularly described and pointed out hereinafter.

Referring to the accompanying drawings, Figure 1 is a top plan view of a railway-track provided with my improved third rail, the 25 power-generator of the system and the car-motor, magnet, contact, and general car-circuits being shown in diagram. Fig. 2 is a longitudinal section of the electric rail. Fig. 3 is a cross-section on the dotted line 3 3 of Fig. 30 2; and Figs. 4 to 12, inclusive, are partial longitudinal sections of the improved third rail and showing several modifications of the invention.

In the drawings, *a a* are the track-rails, suitably secured on the cross-ties *b b*.

c is the electric rail laid along the track parallel with and preferably, although not necessarily, between the track-rails. For suburban systems the electric rail is usually 40 spiked down on or otherwise secured to the cross-ties. In the construction of city-ways the electric rail is usually secured in the road-bed on suitable cross supports or ties and protected by the paving. The electric rail is 45 composed, essentially, of non-conducting and non-magnetizable material, such as wood. For instance, I show a wooden body or stringer *c'*, having a top longitudinal groove formed therein. A U-shaped trough *c²*, of suitable 50 insulating material, is placed in said groove. Said trough is, preferably composed of some suitable refractory ceramic material, such

as porcelain, molded in sections of suitable length to fit loosely or snugly, as desired, in the groove cut in the wooden body of the rail. 55

c³ is the exposed sectional conductor sealing the groove, trough, or conduit of the electric rail. This conductor is formed in sections, the sections suitably insulated from each other by interposed blocks of insulating 60 material. I show the exposed conductor composed of bars U-shaped in cross-section or having depending edge flanges, so that the bar fits the top of the electric rail and the flanges extend down at the sides thereof. The 65 bar thus closes and seals the conduit, and its under surface is exposed at the open top of the porcelain trough.

The rail is usually protected, and the sectional exposed conductor is held in position 70 by any suitable means, such as longitudinal side strips *c⁴* on opposite sides of the rail and longitudinal outside angle-irons or otherwise-formed metal plates *c⁵*. The parts can be locked together by suitable securing devices, 75 or the spikes *c⁶*, securing the electric rail to the cross-ties or track-supports, can be depended on to lock the parts together. However, I merely show and describe this form of rail for the sake of illustration, and my invention is not limited to any particular form or construction of electric rail. 80

d is the live movable line-wire, electrically connected with the power-generator *p g* of the railway system in any suitable manner. This 85 line-wire is composed of good conducting and magnetizable metal, and, so far as I am at present advised, I prefer to use a stiff iron wire for this purpose.

As shown by diagram in Fig. 1, the motor-car is provided with a suitable magnet *c m*, moving over the electric rail and attracting the line-wire up into engagement with the sections of the exposed conductor successively, and a car-contact *c c* moves on said sections 95 and conducts off the power-current, which is passed to the car-motor *c¹² m¹²*. However, I do not wish to limit my electric rail necessarily to employment in such a system.

In view of the peculiar nature of the stiff 100 iron wire *d* generally employed longitudinal expansion and contraction might in very long lengths cause lateral displacement, such as kinking and bending of the wire, and conse-

quent danger of charging exposed conducting portions of the rail. To guard against such possibilities and to avoid mechanical difficulties incident to the displacement of long 5 lengths of the stiff wire in the electric rail and in handling the same, I form the wire in sections with their ends separated. The sections have their ends separated any suitable distance, which, however, I prefer should be 10 of such length as to avoid contact of said ends under the maximum longitudinal expansion of the sections.

I form depressions or seats in any suitable manner or by any suitable means in the floor 15 of the conduit beneath or at the breaks between the sections of wire. For instance, where the porcelain trough is employed, in the bottom of which said line-wire loosely rests, said depressions can be formed by breaks in 20 the trough, as shown in Figs. 2 and 3. The trough is formed in sections, and at the proper intervals in the rail the ends of two adjoining sections are separated a suitable distance to form the bottom depression d^2 . The line- 25 wire sections preferably end at said break, and said wire sections are mechanically and electrically connected by suitable expansible or flexible conductors d^3 across the depression d^2 and the break in the porcelain trough. 30 Said conductor is shown formed of heavy wire coiled or looped to expand and contract longitudinally and take up the longitudinal expansion of the line-wire. The ends of the expansible connection are suitably secured 35 to the ends of the line-wire sections. The depression receives the expansible connection and avoids upward movement thereof or location thereof dangerously close to the exposed conductor-section above, and at the 40 same time the electric conductors are maintained in their proper positions.

The conduit or groove of the electric rail is provided with an enlargement opposite the extensible portion of the conductor or that 45 portion of the conductor within the conduit which is of increased diameter and which may possibly move laterally or vary in diameter as the conductor expands and contracts longitudinally.

50 A conductor can be formed, if desired, with a spring-coil within its length, which will not only take up the expansion and contraction, but will maintain the proper tension on the conductor and keep it loosely in proper position.

55 The wire need not necessarily be cut into mechanically separate and distinct sections ending at each extensible portion; but the conductor can be formed with expansible portions, dividing the wire into sections by coiling or looping the wire within its length—that is, by forming the wire with expansible portions integral therewith. The extensible portions or connections in the conductor can be 60 arranged at suitable intervals or at suitable distances apart along the electric track, ac-

cording to conditions and the requirements of the particular system.

In Figs. 4 to 12, inclusive, I illustrate several modified forms of the invention, and they 70 will be understood in view of the foregoing description without detailed explanation. The flexible or yielding conductor-section d^3 in Fig. 4 is a **U**-shaped piece of spring metal having its horizontal members in position intermediate the adjacent ends of the line-wire sections and secured thereto. In Fig. 5 the expansible or flexible conductor-section d^3 is 75 simply a flattened portion of the line-wire bent into **U** shape. The section d^3 in Fig. 6 80 corresponds with the construction shown in Fig. 5, except that the wire, being lighter, is not flattened. In Fig. 7 the section d^3 is simply a wire coil below the lighter conductor m , and in Fig. 8 the line-wire is looped, as shown, 85 to form the section d^3 , and the lower end of this section is fastened down by a yielding spring x . In Fig. 9 the section d^3 is formed by giving the stiff iron line feed-wire a circular coil below the movable lighter conductor 90 m . Fig. 10 illustrates the two wires, each having a section d^3 , while in Fig. 11 it is shown that only one of said wires has a section d^3 . The two wires in Fig. 12 each has a section 95 d^3 , one being in the form of a coil and the other approximating the shape of the letter **U**. In instances in which the one wire d is made use of said wire will be magnetizable material, such as iron; but when the lighter vertically-movable conductor m is also employed 100 the feed-wire d will preferably be of copper and the wire m of magnetizable material.

The rail structure shown in this application is made the subject of a separate application for Letters Patent filed by me on February 9, 105 1901, and bearing Serial No. 46,608.

It is evident that various changes might be made in the forms, constructions, and arrangements of the parts described without departing from the spirit and scope of my invention. Hence I do not wish to limit myself to the specific devices shown or set forth.

What I claim as my invention, and desire to secure by Letters Patent, is—

1. In an electric rail the movable stiff line-wire formed in divisions or sections, and an extensible connection between the sections, the rail-conduit having an enlargement opposite said connection, substantially as described. 115

2. The electric rail having its internal conduit having a bottom depression, and a conductor in the conduit including a portion at said depression to take up longitudinal contraction and expansion, substantially as described. 120

3. In an electric rail having an internal conduit, a continuous conductor therein provided at intervals along its length with the expansible portions forming parts of said continuous conductor and adapted in themselves to take up longitudinal expansion and 125

contraction in said conductor; substantially as and for the purposes set forth.

4. The electric rail having a conduit within itself, an insulating-trough therein having at 5 intervals, the recesses, and a conductor in the trough having extensible portions at said recesses, substantially as described.

5. The electric rail having therein the continuous conductor provided integrally there- 10 with at suitable intervals with the looped portions adapted to take up longitudinal expansion and contraction in said conductor; substantially as and for the purposes set forth.

15 6. In an electric rail the continuous feed-wire having at suitable intervals along its length the extensible portions forming parts of said continuous conductor and adapted to take up longitudinal expansion and contrac- 20 tion in the same, combined with the lighter conductor on said feed-wire and also having

at intervals along its length the extensible portions forming parts thereof to take up longitudinal expansion and contraction therein; substantially as and for the purposes set 25 forth.

7. In an electric rail the continuous feed-wire having at suitable intervals along its length the extensible portions forming parts of said continuous conductor and adapted to 30 take up longitudinal expansion and contraction in the same, combined with the lighter conductor on said feed-wire; substantially as and for the purposes set forth.

Signed at New York, in the county of New 35 York and State of New York, this 26th day of January, A. D. 1901.
